UNITED STATES PATENT OFFICE.

JOSEPH FRACKMAN, OF NEW YORK, N. Y.

SETTING FOR PRECIOUS STONES.

1,171,186.

Specification of Letters Patent. Patented Feb. 8, 1916.

Application filed August 18, 1915. Serial No. 46,129.

To all whom it may concern:

Be it known that I, JOSEPH FRACKMAN, a citizen of the United States, and a resident of the city of New York, in the county 5 of New York and State of New York, have invented certain new and useful Improvements in Settings for Precious Stones, of which the following is a specification.

The present invention relates to a setting 10 for precious stones.

In the manufacture of jewelry, it is customary to mount a number of small stones in a cluster to resemble a single stone of the size of the cluster. It has also been 15 customary to attach to the plate or disk, in which the small stones are set, a frame-work to resemble the facets of the pavilion of the single large stone to be imitated. This frame-work is either produced by a plurality of wires, which are secured to the 20 disk and extend downward and meet in the axis of the disk, or the said facets are formed of a plurality of metal plates. Both of these constructions have been found to 25 be detrimental to the brilliancy and beauty of the small stones forming the cluster, for the reason that the first construction darkens the center stone of the cluster, and the second construction darkens all stones with 30 the exception of the central stone, provided that the metal plates stop short of the axis of the disk.

It is now one of the objects of the present invention to obviate these defects by producing a simple and inexpensive structure 35 in which all stones of the cluster retain their original brilliancy and beauty.

With these and other objects in view, which will more fully appear as the nature 40 of the invention is better understood, the same consists in the combination, arrangement and construction of parts hereinafter fully described, pointed out in the appended claims and illustrated in the accompanying 45 drawings, it being understood that many changes may be made in the size and proportion of the several parts and details of construction within the scope of the appended claims without departing from the 50 spirit or sacrificing any of the advantages of the invention.

One of the many possible embodiments of the invention is illustrated in the accompanying drawings, in which:

55 Figure 1 is a side elevation of a ring with the improved setting; Fig. 2 is a plan view

of the setting, the stones being removed to more clearly show the construction; Fig. 3 is a bottom plan view of the setting; and Fig. 4 is a section taken on line 4—4 of Fig. 3.

In the drawings, the numeral 10 indicates a metallic circular disk, which is slightly raised toward its center, and provided with a plurality of apertures 11, one of the same being formed in the center of the disk and the others grouped around the same. Into these apertures are set the small precious stones 12. To cause the structure to resemble a single stone, a frame-work 13 is attached to the underface of the disk 10, said frame-work being made of wire and being star-like. The points 14 of the radiating arms of the star-like structure are suitably fastened, for instance, by solder to the periphery of the disk 10, its radiating arms 15 extending from there downward in inclined positions toward the axis of the disk, but stopping short of such axis. The central stone forms thus the table of the single stone to be imitated, the periphery of the disk the girdle thereof, and the radiating arms of the frame 13 the edges of the facets of the pavilion of such stone. The frame 13 is preferably made of a single 85 piece of wire, properly bent and shaped.

It is to be observed that the radiating arms of the frame 13 are disposed in relation to the apertures 11 in such a manner that access of light to such apertures from below 90 is in no way obstructed. On the other hand, attention is called to the fact that, inasmuch as the radiating arms stop short of the axis of the disk 10, the central aperture is not 95 obstructed. The radiating arms of the frame stop short of the axis of the disk for another reason also, to wit: to form the collet of the stone.

The setting now described may be mounted, for instance in a ring 16, as shown in Fig. 1 of the drawings, or in earrings, pins, brooches, etc.

What I claim is:

1. A setting for a cluster of small stones, comprising a disk provided with a plurality of apertures into which the stones are fitted, and a frame-work attached to said disk, said frame-work being made in the form of a star-like structure having the points of its radiating arms secured to the periphery of said disk, said arms being out of alignment with said apertures and extending in

inclined positions downward toward the axis of said disk, but stopping short of said axis.

2. A setting for a cluster of small stones, comprising a disk provided with a plurality of apertures into which the stones are fitted, and a frame-work attached to said disk, said frame-work being made of a single piece of wire in the form of a star-like structure having the points of its radiating arms

secured to the periphery of said disk, said arms being out of alinement with said apertures and extending in inclined positions downward toward the axis of said disk, but stopping short of said axis.

15

Signed at New York, in the county of New York, and State of New York, this 16th day of Aug., A. D. 1915.

JOSEPH FRACKMAN.

Copies of this patent may be obtained for five cents each, by addressing the "Commissioner of Patents, Washington, D. C."
